UNITED STATES PATENT OFFICE.

WILHELM HIRL, OF BERLIN, GERMANY.

PIANO.

SPECIFICATION forming part of Letters Patent No. 441,559, dated November 25, 1890.

Application filed June 24, 1887. Serial No. 242,353. (No model.)

To all whom it may concern:

Be it known that I, WILHELM HIRL, of the city of Berlin, Prussia, Germany, have invented certain new and useful Improvements 5 in Piano-Fortes, of which I declare the following to be a true and correct specification.

My invention consists in combining with two independent key-levers and their actions a lever adapted to be moved between them 10 and pivotally connected to a second lever which is moved forward and backward by a rod, so that the first lever will be moved between or away from the two key-levers.

In order to more clearly illustrate my said 15 invention and enable those versed in the art to readily carry the same into effect, I have represented my improved construction on the accompanying drawings, in which—

Figure 1 represents the sectional view of a 20 piano-forte provided with the improved mechanism; and Fig. 2, a side view of the coupling device in an uncoupled position, drawn on an enlarged scale.

In the interior central part of the piano-forte I arrange a vertical double sound-board 25 A' and A'', which said sound-board carries at its upper ends two tuning-pin rails B B', on both sides of which the strings or wires b and b' are strung by means of the tuning-pins a a'.

These cords or wires b b' are struck or acted 30 on by the hammers C C', which latter are constructed, arranged, and combined with the necessary dampers in the well-known manner. The hammer mechanism c is brought in connection with the key-lever f by means of 35 the vertical rod d, whereas the mechanism designated c' is operated by and movably arranged on the horizontal lever h through the connecting-rod d'. This lever h rests and

40 turns on the fulcrum g, and is connected at its lower end with the key k by means of rod i. The key k of the lower key-board is located or fixed immediately beneath the key f of the upper manual, and is provided with a 45 nose or projection k', which impinges against or is brought in contact with an intermediate small lever n, the latter being movably arranged on n', which in its turn is attached to a lever m, swinging or turning on the ful- 50 crum l. A horizontal rod or stop o, provided

with a knob or button o', is arranged between the keys f and k, and is suitably connected with or attached to lever m. If now the stop o is pulled out, the small lever n will be drawn

between the nose k' and the key-lever f, as 55 represented in Fig. 1 of the accompanying drawings. By depressing the key k when the mechanism is in this position the rods i and d' will be raised and the key f and rod d pressed up, so that the hammers C C' will 60 be caused to simultaneously strike the wires b and b', and thereby considerably increase the strength of tone. Both sets of cords or wires are naturally tuned in unison. If the stop o is now pushed inward, the coupling 65 will be disconnected and only the hammer C' caused to strike the wire or string b' by operating on the key k, whereas even if the lever n is in a coupled or uncoupled position action 70 will be imparted only to hammer C by depressing the key f. The pedal p rests on the one end of a two-armed lever r, which is pivoted at q, and which with its other end abuts against the lower part of the lever h, which latter, as previously mentioned, is movably 75 attached at g. If pressure is exerted on said pedal when the small lever n is in the position shown in Fig. 1—i. e., so as to couple the keys f to the keys k—both cords or wires b and b' will simultaneously be operated on in 80 the manner hereinbefore set forth, whereas when lever n is uncoupled, as in Fig. 2, only hammer C' and cord b' will be acted on.

I am aware that it is old to employ two sets 85 of strings, a front and rear action, and provide means whereby said actions may be operated simultaneously or separately, and I make no claim to this broadly.

Having now particularly described and ascertained the nature of my said invention 90 and in what manner the same is to be performed, I declare that what I claim, and desire to secure by Letters Patent, is—

In combination with the two independent key-levers connected to the two actions, the 95 lever n, arranged on pivot n', a lever m, pivotally supported and carrying the pivot n' and lever n, and the rod o, provided with a knob for operating the lever m and causing the lever n to go between the two sets of keys, 100 substantially as described.

In witness whereof I have hereunto signed my name in the presence of two subscribing witnesses.

WILHELM HIRL.
